RECORDING INSTRUMENT

William K. Matheson, Brooklyn, N. Y., and
Arthur C. Homeyer, Glen Ridge, N. J.

Application December 1, 1937, Serial No. 177,478

16 Claims. (Cl. 234—72)

This invention relates to recording instruments.

More particularly, this invention relates to instruments in which a primary element, responsive to variations in external conditions, moves an indicating element which embodies or in turn actuates a stylus, printing device, or other means for inscribing a legible record of such external condition upon a chart or tablet graduated in appropriate units, such legible record being continuous over a predetermined time period.

In this invention, the stylus or equivalent and its therewith associated primary actuating element are preferably pivotally mounted upon a carriage movable relatively to a fixed chart, the carriage movement, in at least one direction, being at a definitely controlled or "timed" rate. The stylus, in accordance with common practice, is arranged to respond to the movement of the primary actuating element per se, the stylus movement being preferably substantially at right angles to the direction of carriage movement.

It is a feature of this invention that a reverse movement of the carriage, i. e., a movement in a direction other than that of the "timed" movement thereof, is effective immediately to raise the stylus clear of the chart, such raised position being maintained until manually operable repositioning means are actuated.

It is yet another feature of this invention that the mounting of the stylus and primary actuating element on a movable carriage permits an appreciable simplification of the timing mechanism, a simple clock-escapement or equivalent means adequately controlling the rate of carriage movement. Any conventional power means for actuating the clock-escapement may be employed; however, a spring-motor drive for such escapement finds particular advantage in making the instrument entirely independent of external power, such as electric power. Additionally, the reverse movement of the carriage may be concomitant with the winding of the spring motor, the fully wound status of such spring motor most preferably coinciding with the positioning of the stylus at and above the datum time line of the chart, in which circumstance, operation of the stylus-resetting means is effective to re-position the stylus on the chart, and to position it accurately at or on the datum line. It will thus be obvious that the stylus may be at the datum time line only in the circumstance of a fully wound spring motor, thus precluding any possibility of the motor "running down" before the desired travel of the pen over

the established time period has been completed.

A further feature of the invention resides in means for automatically halting the clock-escapement movement at a suitable time after the completion of carriage travel, the clock-escapement automatically being restored to full operative status upon rewinding the spring of the clock-escapement motor.

Other features and advantages will herein-after appear.

In the accompanying drawings:

Fig. 1 is a perspective of a recording instrument made pursuant to the present invention;

Fig. 2 is a plan view, partly in section, taken through the points 2—2 of Fig. 1, the position of the indicator and stylus being changed to indicate substantial expiration of the time period of the record;

Fig. 3 is an elevation of the carriage and its therewith associated primary element;

Fig. 4 is an elevation, taken through 4—4 of Fig. 2;

Fig. 5 is a sectional elevation of the primary element, taken through 5—5 of Fig. 2, detailing its mounting in the carriage;

Fig. 6 is a plan section of the carriage, taken through 6—6 of Fig. 3, the position of the cam and cam pin being slightly altered with respect to Fig. 3, for clarity;

Fig. 7 is an elevation, partly in section, illustrating the position of carriage and stylus on the completion of wind of the spring motor of the escapement means;

Fig. 8 is a plan section taken through 8—8 of Fig. 7, the position of the carriage being in this figure at the extreme upper limit of travel; Fig. 8 further indicates the operation of the escapement-stopping means;

Fig. 9 is a vertical section of the escapement mechanism and associated structure, taken through 9—9 of Fig. 8;

Fig. 10 is a bottom view, showing the manual carriage-adjustment lever;

Fig. 11 is an exploded perspective of the manual carriage-adjustment organization; and

Fig. 12 is a perspective of the slideable carriage and its associated cam means.

A recording instrument 10, see Figs. 1 and 2, includes a "primary" element 11, sensitive or responsive to external conditions, an indicator 12 associated with said primary element and arranged to be moved or otherwise actuated thereby, a stylus 13 or equivalent marking or printing device, preferably unitarily combined with said indicator and arranged to inscribe a

legible record on a suitably delineated chart or tablet 14, and means providing for such inscription or record to continue over an established time period, such means including a timing mechanism 15, a carriage 16 arranged to support said primary element and said stylus, guide-rods or trackway 17 on which carriage 16 may be slidably mounted for travel toward or away from said chart, and means such as the 10 spring motor 18 for moving the carriage.

By an element "sensitive to external conditions" as used hereinafter, and in the appended claims, is meant a structure preferably so affected by conditions such as ambient temperature, condition of pressure, electric current, mechanical motion or the like, as to be physically altered in varying degree by the intensity or value of such external condition, the physical alteration being most preferably a movement or 20 displacement of such element of suitable magnitude.

As typical of a recording instrument made pursuant to this invention, the primary element 11 is illustrated as being a conventional bi-metallic 25 coil, said element tending to uncoil under conditions of rising temperatures and to coil under conditions of falling temperatures. Such type of bi-metallic coil is well known to those skilled in the art. The recording instrument illustrated 30 is thus adapted to record ambient temperatures; however, the exact form or type of response of primary element is not an essential feature of this invention.

For a suitable housing and supporting structure 35 the recorder 18 may have a pressed metal or equivalent base 20 on which a cover 21 may be pivotally, and preferably removably, mounted. Ventilation slots as shown at 22, Fig. 1, preferably coextensive with the full travel of the carriage, are in conformity with the function of the instrument as a recording thermometer; the cover of a mechanical motion recorder, electrical measuring instrument, or the like, need not be ventilated to such extent.

45 Cover 21 may be provided with an opening 23, rendering the chart 14 visible behind a suitable transparent protective window.

Carriage guide rods 17 may be supported in parallelism, and in suitable spaced relationship 50 to base 20, on a suitable rear angle member 25 and a front wall 26 of a casing 27 arranged to house the timing mechanism 15 and its associated structure. Projecting tips 28 at the terminal ends of rods 17 may snugly engage suitable holes 55 in the supporting members 25, 26 to position the rods 17. A table or "chart plate" 30 suitably supports the chart 14. Screws 31 serve to hold casing 27 removably on base 20.

Chart 14 may be positioned on the chart plate 60 by suitable side plates 32 and end lugs 33; longitudinal spring members 34 secured to side plates 32 serve to press the chart 14 yieldably against the chart plate. The chart may thus be slid forwardly beneath springs 34 until the forward 65 edge of the chart abuts against the lugs 33.

The inner end of primary element 11 may be secured to a spindle 35 supported for free axial rotation in a yoke formed by a superstructure member 36 of carriage 16 and an upper bridge 70 member 37, member 37 being suitably secured by means of posts 38 and nuts 40. The outer end of the primary element is suitably anchored. The primary element is preferably of such organization of dissimilar metals that a reduction in 75 temperature causes a coiling of the primary ele-

ment and corresponding clockwise rotation of the spindle 35, whereas a condition of increasing temperature urges the spindle into counter-clockwise rotation. The upper end 35a of spindle 35 receives a collar 41 to which the indicator 12 is fixedly secured. The response of element 11 to temperature variations—i. e., its response to "external conditions"—therefore causes the indicator and its associated stylus 13 to swing appropriately across the chart 14. Preferably the indicator is counter-weighted as by a weight 42 of suitable magnitude.

Calibration of primary element 11 may be effected by a displacement of its bifurcated anchor member 43 to the right or left, as viewed in Fig. 2, such movement enforcing a rotation of spindle 35 in desired degree. The necessary movement of member 43 may be accomplished by an adjustment mechanism including an adjustment screw 45, see Fig. 12, passing through a suitable opening in a vertical ear 49 of an angle-shaped slide member 47 and into a female-threaded hole in a post 48, the latter being fixedly supported on member 36 by a neck-portion 52, Fig. 4, which additionally functions as a fastening rivet. The neck 52 suitably positions the head of post 48 above the member 36, and provides for slidably confining the base portion of slide member 47 between the member 36 and the head of post 48, the neck 52 passing through a suitable slot 51 in the base of member 47. The length of slot 51 therefore establishes the amount of movement of the slide member 47. On screwing the adjustment screw 45 inwardly, the head thereof, bearing against ear 49, drives the slide 47 to the left, against the resistance of a spring 48 interposed between the ear and the post 48. On unscrewing the adjustment screw, the expansion of spring 48 urges the member 47 to the right. A pin 50, secured to an end of member 47 and passing through the bifurcated portion of anchor member 43 operatively associates the primary element 11 with the adjustment mechanism, to effect desired rotation of the spindle 35.

Carriage 16, see Fig. 12, further includes a base 54 suitably mounted on guideways 17 so as to be freely slidable thereon. Advantageously, base 54 may have a downwardly depending flange 55, see Fig. 6, at the rear thereof, and a similar 50 flange 56 at its forward portion. Holes suitable for passage of rods 17 therethrough are provided in these flanges, the single hole in flange 56 being in alignment with one of the two holes in flange 55. The second of the two holes in flange 55, 55 see 57, Fig. 6, may be elongated to provide for suitable play of rod 17 passing therethrough and thus insure the free travel of the base 54 on the rods 17. Accordingly, base 54 is supported on the rods 17 at three points of mount. The base 54 further includes downwardly extending side plates 58, said side plates forming members on which the superstructure 36 may be pivotally mounted, side plates 59 of the latter suitably overlying plates 58. The transverse pintle 60 55 provides for such pivotal support.

In this invention, the timed travel of stylus 13 is accomplished by moving the stylus 13 over a fixed chart 14, the "time datum line" 14a of the chart being at the bottom thereof, see Fig. 2. 70 Full travel of stylus 13 may be as desired, that of the illustrated embodiment being effected in twenty-four hours.

To accomplish the timed travel of the stylus 13, means are provided whereby the entire car- 75

riage 16, supporting the primary element, indicator, stylus, and associated elements, moves away from the chart 14 at a definitely controlled or timed rate. The motive power for the carriage 5 may advantageously be the tensile spring 18; the rate of movement may be governed by the timing mechanism 15, which opposes the pull of the spring means 19.

Timer 15, as illustrated, may be spring-motor driven, such type of motor making the escapement entirely independent of external power source. The spring-motor 62 may have a drum 63, see Fig. 7, on its shaft 61, on which drum may be wound and suitably secured a portion of a cable 65. The cable may be carried around an idler spool 66, pass through a suitable opening 67 (see Fig. 8) in front wall 26 of housing 27, extend parallel to guide rods 17, thence around a sheave 68 rotatably secured to base 20, and finally attach to the spring 18, the latter preferably being anchored, as by a pin 70, to the base 20.

It is preferred to secure carriage 16 to the stated cable 65 in a manner providing for ready adjustment and/or removal of the carriage. Accordingly, a plate 71 and screw 72 may be arranged to clamp the cable tightly against one of the side plates 58 of carriage sub-structure 54.

The spring-motor 62, driving or rotating in a direction counter-clockwise of Fig. 2, may be governed in its rate of rotation by conventional escapement means 75. Such rotation of spring-motor 62 and its therewith associated cable-drum 65 permits an unwinding of the cable and concomitant rearward travel thereof under the pull of the spring 18. The carriage structure 16, being clamped to cable 65 is thus drawn rearwardly away from the chart 14. In other words, the pull of spring 18 on the cable 65 is opposed and controlled by the timed unwinding of the cable 40 65 on its drum 63.

Advantageously, the length of the cable is of such dimension that at the completion of the maximum carriage travel, such maximum being established by the rear angle member 25, a quantity 45 of cable equivalent to several hours of additional spring-motor movement remains wound on the drum 63. Means are provided, as later described, for stopping the action of the spring-motor prior to the complete unwinding or release of the cable. The drum 63 is preferably 50 of such diameter and surface area that the cable, when wound thereon to full required extent, is arranged in a single layer, thus insuring an even "paying off" of such cable for each rotation of the drum 63.

It is a feature of the invention that the superstructure 36 of the carriage 16 may be inclined or canted with respect to the carriage, such movement affording means for lifting the stylus 13 clear of the chart in the circumstance of removing or replacing the chart, and/or in the circumstance of bringing the stylus into register with the datum time line on starting a new record run.

Desirably, such canting of the superstructure 65 may be effected automatically on a suitable reverse movement of the carriage, i. e., movement of the carriage in the direction of the chart, as distinguished from its timed or controlled movement away from the chart.

In this invention, the reverse carriage movement may be accomplished in either one of two ways: by the manual operation of suitable adjustment lever means, as later described, or by winding spring-motor 62, the latter operation 75

causing a rotation of its associated drum 63 clockwise of Fig. 2 with a resultant winding of cable 65 on the drum and movement of carriage 16 in the direction of the chart.

To rock the superstructure 36 rearwardly on its pintle 60, the full extent of such rocking movement being illustrated in Fig. 7, cam means may advantageously be used. Such cam structure may include an L-shaped frame 76, see Fig. 6, having suitable perforations to permit the passage of guide rods 17 therethrough, said frame thereby being slidably mounted on said rods in a manner similar to that of base 54 of carriage 16. The frame 76 is preferably frictionally held against free movement along the rods by a leaf 15 spring 77 suitably secured to a side arm 78 of frame 76 and arranged to bear against one of the rods 17 as indicated in Fig. 6.

Further, the cam structure includes a pin 80 fixedly secured to the side arm 78 and projecting 20 at right angles therefrom, as indicated in Fig. 6. As shown in Fig. 3, the superstructure 36 of the carriage is provided with downwardly extending side plate 81, provided with a suitably sloping cam slot 82, the disposition of side plate 81 and 25 slot bringing the latter into cooperative alignment with the cam pin 80.

As above stated, the cam frame 76 is held against free movement along the guide rods 17. However, during movement of the carriage 16 30 in either of its two permitted directions, one or the other of the ends of the cam slot 82 will engage the pin 80, whereupon on continued movement of the carriage, the cam frame 76 and its associated structure will be drawn in the direction of carriage movement. During the "timed" movement of the carriage 16, i. e., movement away from the chart 14, the forward or higher end of the slot engages the pin 80, see Fig. 3; desirably, an operative, i. e., chart inscribing position of stylus 13 is attained just prior to the slot-end and pin engagement. It will be thus obvious that during the entire rearward movement of the carriage, the stylus will be in full operative position. 40 45

When it is desired to cant the superstructure 36, and thus to raise the stylus clear of the chart, the carriage 16 may be moved in the direction of the chart. The cam frame member 76 being frictionally held against displacement, the carriage 16 may be moved toward the chart without effecting a similar immediate movement of the stated cam frame. The carriage movement causes the sloping cam slot to bear against stationary pin 80, and accordingly, the effect of the 55 slope of such cam slot is to tilt the superstructure 36 into the position shown in Fig. 7. At the completion of the camming movement, the rear or lower end of the slot 82 engages pin 80, and continued movement of the carriage structure 60 in the direction of the chart draws cam frame 76 in the same direction.

It is a feature of this invention that the organization of carriage 16, and the arrangement of drive cable 65 with respect to the drive motor 62 brings the stylus 13 to a position at and above the datum time line of the chart 14 coincidentally with the fully wound status of the spring-motor 62. It will be obvious, therefore, that at the start of a record run, the spring-motor is necessarily 70 in fully wound condition.

An adjustment lever 85, see Figs. 10 and 11, may be employed to cant the superstructure 36 when desired to raise the stylus clear of the chart, and finds a further application in bringing the stylus 75

into operative contact with the chart, after the operation of winding the spring-motor. In accordance with the method of canting the superstructure previously set forth, it is necessary to cause a suitable movement of the carriage to effect the resultant desired operation of the cam means thereof. Such movement of the carriage may be accomplished either by winding the spring-motor, as described, or by displacing the idler spool 66, such displacement being under the control of the adjustment lever 85. Referring now to Figure 11, in which the adjustment lever organization is illustrated in exploded perspective, and to Fig. 9, a spring washer 83, a follower 84, an arm 86, carrying spool 66 rotatably at one end thereof, and a balance-wheel stop 87 are pivotally mounted, in the order named, on a common shaft 88, said shaft having a rivet head 90 supporting lever 85, and provided with a nut 91 to integrate the assembly.

Particularly, see Fig. 9, lever 85 and spring washer 83 are disposed beneath the base 20, follower 84 rests on the base, and arm 86 is carried directly on follower 84. The follower is provided with a downwardly projecting tongue 92, which passes through a suitable slot 93, see Figs. 8 and 10 in the base 20, and engages the lever 85 by passage through a suitable hole 94 therein, the diameter of the latter restricting play or backlash of tongue 92 therein to a minimum. Thus, a movement of the lever 85 about the common shaft 88 causes an identical movement of the follower 84. The tongue 92 serves additionally as a means of limiting the travel of lever 85, by contacting one or the other end of the slot 93. The arm 86 has formed at a side thereof a short tongue 95, preferably projecting below the bottom surface of arm 86 to an extent slightly less than the thickness of the material of follower 84. The tongue 95, by being in the path of movement of follower 84 when the latter is moved in direction clockwise of Fig. 8 on suitable manipulation of lever 85, thereby causes the arm 86 to move in that direction. However as appears in Fig. 8, the arm 86 may have such clockwise movement entirely independent of and greater than that of the follower 84 and its therewith associated lever 85. A knob, as 85a, may provide for ready manipulation of the lever 85.

Normally, the pull of spring-motor 18 urges the arm 86 into rotation counter-clockwise of Fig. 2, and thus keeps tongue 95 at all times in contact with an edge of follower 84. When the lever 85 is in position which may be substantially at right angles to the line of travel of the carriage, indicated by the dotted line in Fig. 2, the superstructure 36 and its therewith associated primary element, indicator, and stylus, may be in the Fig. 3 position, that is, chart inscribing position. Should it be desired to lift the stylus clear of the chart, as in the circumstance of changing the chart, the lever 85 may be moved clockwise of Fig. 8 to the extent permitted by the slot 93. Such downward movement causes a following movement or rotation of arm 86 and idler 66, and therefore moves the carriage 16 toward the chart. Immediately, the cam and slot organization of the carriage functions to cant the superstructure and raise the stylus clear of the chart. The friction washer 83 is effective to hold the lever 85 in any position, against reaction of the spring-motor 18.

Upon manual return of the lever 85 to its normal position, the spring-motor 18 holds the tongue 95 in contact with an edge of follower 84, and thus the arm 86 and its mounted idler 66

move counter-clockwise of Fig. 2 with an accompanying rearward movement of carriage 16. By the automatically following operation of pin 80 and cam slot 82, the stylus is returned to operative position on the chart. Desirably, when the stylus is in such operative position, the movement of lever 85 to the full extent permitted by slot 93 has not been utilized, thus providing for additional rearward movement of the carriage for purposes of adjustment of stylus 13 on the chart. 10

At the termination of the spring-motor winding operation, the stylus 13 will have been brought to a point at and above the datum time line 14a of the chart. The operation of winding the spring-motor holds the lever 85 and associated structure 15 against accidental displacement. To bring the stylus 13 into operative contact with the chart, it is necessary to rotate the superstructure downwardly, such superstructure movement necessitating an appropriate movement of the carriage 16. 20 For effecting such movement, lever 85 may be rotated clockwise of Fig. 8, to the limit permitted by slot 93. Such movement of lever 85, as indicated in broken line in Fig. 7, serves to move the entire carriage 16 an additional step in "reverse" 25 direction, the amount of such step being preferably greater than the projected effective length of the slot 93. Such manipulation of lever 85 therefore moves the stylus, still clear of the chart, beyond the datum time line, as represented in Fig. 30 7, and also moves the cam frame 16 a similar amount. On the return of lever 85 to its Fig. 10 position, the spring 18 is permitted to draw the carriage rearwardly. The cam base 76 remaining stationary by reason of the frictional contact 35 of spring 77 with the guide rod 17, the pin 80 and cam slot 82 function to swing the superstructure 36 in a direction counter-clockwise of Fig. 7, and thus the stylus is positioned on the chart, at the datum time line.

Desirably, the spring of spring-motor 62 has an appreciable factor of safety. For example, when the carriage travel has completed its full record run, the carriage at such stage closely approaching the angle member 25, the spring-motor 62 will 45 continue to function for several additional hours, such continuing function of the motor permitting the carriage to reach its extreme limit of travel, as established by the abutment thereof against angle member 25. To avoid a slackening 50 of the cable 65 on continued rotation of spring-motor drum 63 and thus to obviate any possibility of the cable dropping away from the spool 63, means are provided to rotate the arm 86 clockwise of Fig. 8, thus serving to take up slack of the cable 65. Such clockwise rotation may result 55 from the action of a suitable tensile spring 96 anchored to a post 97 on the base 29 and attached to a suitable ear 98 on the arm 86. The strength of the tensile spring 96 is purposely insufficient to 60 overcome the pull exerted by the spring-motor 18. However, when the carriage 16 comes to rest against the angle member 25, the spring 18 is no longer effective, and the tensile spring 96 need only overcome the frictional resistance of arm 86. 65 Desirably, such movement of the arm 86 may be utilized to cause the spring-motor to stop, by stopping the escapement balance-wheel 75a. Advantageously, a flexible, light finger 87, may be arranged to be rotated by the arm 86, a certain 70 stage of such rotation, preferably four or five hours after the maximum travel of the carriage, serving to bring the finger 87 into contact with the escapement wheel 75a, thus stopping the clock movement. Finger 87 may have an integral 75

body-portion 100 having a slot 101 at an edge thereof, such slot cooperating with a struck-up pin 102 in arm 86 to position the finger 87 and make it movable by the arm 86. The body-portion 100 may additionally serve as a bearing washer for nut 91.

At the commencement of rewinding the spring-motor 62, the clockwise rotation of the drum 63 serves to rotate the arm 86 counter-clockwise of Fig. 8, to a point where its tongue 95 again contacts the side of follower 84. Such movement of the arm 86 frees the escapement wheel 75a of contact with the finger 87, and permits the escapement again to function in normal manner. Continued winding of the spring-motor, as previously stated, returns the entire carriage into position for the commencement of a new time run.

As previously stated, cover 24 is desirably removably secured to base 20. Accordingly, such 20 securing may be effected by a pin- and bayonet-slot organization 103, 104, see Fig. 1. It is of particular desirability that the cover of a recording thermometer of the type illustrated be made removable, as under certain conditions of operation 25 the heat capacity of the cover may slow the response of the primary element to temperature change.

Although it is considered preferable to employ spring-motor 62 in connection with the escapement means, it will be understood that carriage drive motor 18, acting as it does to enforce rotation of the drum 63 may, if desired, be the sole motive power. In such circumstance, rotation of drum 63 would be equally under control of the 30 escapement 75. With such an arrangement escapement stop 87 may be eliminated, as upon completion of maximum carriage travel, motor 18 could induce no further rotation of drum 63.

Desirably, the recorder is entirely of metallic 40 construction, except, of course, for the chart and the chart window. The choice of materials is necessarily influenced by the function of the respective parts; stainless steels and non-ferrous alloys are of particular value in eliminating the 45 possibility of rusting or corrosion in normal use.

Whereas we have described our invention by reference to specific forms thereof, it will be understood that many changes and modifications 50 may be made without departing from the spirit of the invention.

We claim:

1. In a recording instrument having a chart, a carriage movable relatively to said chart, a primary element mounted on said carriage, and a stylus operatively associated with said primary element and arranged to inscribe said chart, the combination with means associated with said carriage for raising said stylus from said chart upon a movement of said carriage in one direction, means for moving said carriage with respect to said chart, means for limiting the amount of carriage movement and timing means for controlling the rate of such carriage movement, of means for stopping further action of said timing means at a predetermined time after the completion of allowed movement of the carriage.

2. In a recording instrument as set forth in claim 1, a pivotally mounted arm supporting the said idler, said arm being held against independent rotation in one direction but arranged to rotate in a second direction, spring means acting on said arm in opposition to the carriage drive means during the stage of timed carriage travel, and urging said arm in the direction of its permitted rotation, and means associated with said

arm and arranged to stop the carriage travel timing means upon the rotation of said arm subsequent to the termination of timed carriage travel.

3. In a recording instrument having a frame adapted to carry a chart, an element sensitive to external conditions, and chart marking means associated therewith and movable thereby with respect to said chart, the combination with a carriage slidably mounted in said frame for movement in the plane of the chart and drive means 10 for moving said carriage in one direction at a timed rate of speed, of a superstructure pivotally mounted upon said carriage for movement of the marking means toward or away from the plane of the chart, said superstructure having said sensitive element supported thereon, and means associated with said carriage for moving said pivoted superstructure to bring said marking means out of chart marking position upon a movement of said carriage in a direction other than the direction of timed movement thereof and to maintain said non-marking position regardless of the extent of such carriage movement.

4. In a recording instrument having a frame adapted to carry a chart, an element sensitive to external conditions, and chart marking means associated therewith and movable thereby with respect to said chart, the combination with a carriage slidably mounted in said frame for movement in the plane of the chart and drive means 30 for moving said carriage in one direction at a time rate of speed, of a superstructure pivotally mounted upon said carriage for movement of the marking means toward or away from the plane of the chart, said superstructure having said sensitive element supported thereon, and means associated with said carriage drive means for reversing the movement of said carriage at any point intermediate the range of timed travel thereof while canting said sensitive element and said 35 marking means with respect to said carriage.

5. In a recording instrument having a frame adapted to carry a chart, an element sensitive to external conditions, and a stylus associated with said sensitive element and movable thereby 45 with respect to said chart, the combination of a carriage slidably mounted in said frame and movable in the plane of the chart, drive means for moving said carriage in one direction at a timed rate of speed, a superstructure pivotally mounted upon said carriage for movement of the marking means toward or away from the plane of the chart, said superstructure having said sensitive element fixed thereon, means acting in opposition to said carriage drive means to move said carriage in a direction other than the timed direction thereof, and means operatively associated with said carriage and said superstructure for swinging said stylus out of operative engagement with said chart during said non-timed movement of said carriage and maintaining such non-operative stylus position during 50 said carriage movement.

6. In a recording instrument having a frame adapted to carry a chart, a carriage slidably mounted on said frame and movable in a plurality of directions in the plane of said chart, drive means for said carriage, means operatively associated with said drive means for timing the movement of said carriage in one direction, and 70 a primary element and a chart-marking stylus operatively associated therewith and movable thereby, the combination of a superstructure pivotally mounted upon said carriage and supporting said primary element and said stylus, 75

- and cam means operatively associated with said pivotally mounted superstructure operative on movement of said carriage during its timed movement to maintain said stylus in chart-marking position, and operative upon movement of said carriage in a direction of movement other than its timed direction of movement to move said stylus out of chart-marking position and maintain said stylus in said position during the extent of said last-mentioned carriage movement.

7. In a recording instrument, the combination with a carriage slidably mounted for movement in a plurality of directions, of a structure mounted on said carriage and means for displacing said structure with respect to said carriage, said means including a pin operatively associated with said carriage, said pin having a limited freedom of action with respect to said carriage, and a cam associated with said structure and arranged for operative engagement with said pin, said cam and said pin operating on movement of said carriage to move said structure with respect to said carriage according to the direction of movement of said carriage.

8. In a recording instrument, the combination with a carriage mounted on guideways and movable thereon in a plurality of directions, of a primary-element supporting superstructure rotatably mounted on said carriage and means for rotating said superstructure with respect to said carriage in a direction determined by the movement of said carriage, said means including a cam-engaging pin slidably mounted on said guideways and cam means associated with said superstructure and disposed in operative engagement with said pin.

9. In a recording instrument, the combination with a carriage mounted on guideways and movable thereon in a plurality of directions, of a structure rotatably mounted on said carriage, a cam frame slidably mounted on said guideways and operatively associated with said carriage, a pin secured to said cam frame, and a cam plate operatively associated with said structure and provided with a cam slot disposed in operative engagement with said pin, whereby upon movement of said carriage with respect to said cam frame said rotatable structure is displaced with respect to said carriage.

10. In a recording instrument, the combination with a carriage mounted on guideways and movable thereon in a plurality of directions, of a structure rotatably mounted on said carriage, a cam frame slidably mounted on said guideways and operatively associated with said carriage, means for restraining free movement of said cam frame, a pin secured to said cam frame, and a cam plate operatively associated with said structure and provided with a cam slot disposed in operative engagement with said pin, whereby upon movement of said carriage with respect to said cam frame said rotatable structure is displaced with respect to said carriage.

11. In a recording instrument, the combination with a carriage mounted on guideways and movable thereon in a plurality of directions, of a structure rotatably mounted on said carriage, a cam frame slidably mounted on said guideways and operatively associated with said carriage, friction means interposed between said cam frame and said guideways for restraining free movement of said cam frame, a pin secured to said cam frame, and a cam plate operatively associated with said structure and provided with a cam slot disposed in operative engagement with

said pin, whereby upon movement of said carriage with respect to said cam frame said rotatable structure is displaced with respect to said carriage.

12. In a recording instrument, the combination with a chart, a carriage movable with respect to said chart, chart-marking means pivotally mounted upon said carriage and arranged for movement into or out of chart-marking position, of drive means for said carriage, clock escapement means operatively associated with said drive means for effecting the movement of said carriage with respect to said chart at a timed rate, means associated with said carriage drive means for reversing the movement of said carriage, means associated with said carriage drive means for moving said chart-marking means out of chart-marking position upon a reversal in the direction of movement of the carriage, and means associated with said carriage-movement reversal means for stopping the operation of said clock escapement.

13. In a recording instrument having a chart, a carriage movable within fixed limits relatively to said chart, a primary element pivotally mounted on said carriage, and a chart-marking stylus operatively associated with said primary element and arranged to be moved into or out of chart-marking position according to the direction of movement of said carriage with respect to said chart, the combination with means for moving said carriage at a predetermined rate of speed with respect to said chart, said means including a clock escapement having a cable drum rotatable thereby at a fixed rate, a drive cable fixed to said cable drum and secured to said carriage, and a motor operatively associated with said carriage and urging said carriage in its timed direction of movement, of means associated with said drive cable to move the carriage in a direction the reverse of the direction of timed movement thereof, and means associated with said last-mentioned means for halting the operation of said clock escapement after the attainment of a predetermined extent of movement of said carriage in the direction of its timed movement.

14. In a recording instrument having a chart, a carriage movable within fixed limits relatively to said chart, a primary element pivotally mounted on said carriage and a chart-marking stylus operatively associated with said primary element and arranged to be moved into or out of chart-marking position according to the direction of movement of said carriage with respect to said chart, the combination with means for moving said carriage at a predetermined rate of speed with respect to said chart, said means including a clock escapement having a cable drum rotatable thereby at a fixed rate, a drive cable fixed to said cable drum and secured to said carriage, and a motor operatively associated with said carriage and urging said carriage in its timed direction of movement, said carriage movement being effected by the paying off of cable from said cable drum, of means associated with said drive cable to move the carriage in a direction the reverse of the direction of timed movement thereof, and means associated with said last-mentioned means for halting the rotation of the said drum subsequently to the limit of movement of said carriage in its timed direction but before the complete unwinding of the cable from said drum.

15. In a recording instrument having a chart and a carriage movable toward or away from

said chart within a fixed limit of travel, the combination with carriage drive means and means acting in opposition thereto to control the rate of movement of said carriage in one of its permitted directions, said control means including a clock escapement having a cable drum operatively associated therewith and rotating at a timed rate, a cable secured at one end to said drum and wound thereon and secured to said 5
10 movable carriage and displaceably mounted idler means for said cable disposed intermediate said drum and said carriage, of means operable to displace said idler means to take up slack in said cable upon the attainment of said maximum permitted travel of said carriage in its timed direction of travel.

16. In a recording instrument having a chart and a carriage movable toward or away from said chart within a fixed limit of travel, the combination with carriage drive means and means acting in opposition thereto to control the rate of 15
20

movement of said carriage in one of its permitted directions, said control means including a clock escapement having a cable drum operatively associated therewith and rotating at a timed rate, a cable secured at one end to said drum and wound thereon and secured to said movable carriage and displaceably mounted idler means for said cable disposed intermediate said drum and said carriage, of means operable to displace said idler means to take up slack in said cable upon the attainment of said maximum permitted travel of said carriage in its timed direction of travel, and means associated with said idler mounting and in operative association with said escapement to halt said escapement and thereupon to halt rotation of said drum at a predetermined time after the attainment of the maximum timed travel of said carriage.

WILLIAM K. MATHESON. 20
ARTHUR C. HOMEYER.
